Primary Examiner — John M Otte(74) *Attorney, Agent, or Firm* — Volpe Koenig**CLAIM**

The ornamental design for a display screen or portion thereof with icon, as shown and described.

DESCRIPTION

FIG. 1 is a view of a first embodiment of a display screen or portion thereof with icon in accordance with the new design; and,

FIG. 2 is a view of a second embodiment of a display screen or portion thereof with icon in accordance with the new design.

The outermost broken lines illustrate portions of a display screen while all other broken lines illustrate elements of a graphical user interface; all broken lines form no part of the claimed design.
